[57] CLAIM

The ornamental design for a tethered jump toy, as shown and described.

DESCRIPTION

FIG. 1 is a perspective view of a tethered jump toy showing our new design;

FIG. 2 is a side elevational view thereof, the side opposite being substantially identical;

FIG. 3 is a front elevational view thereof; and,

FIG. 4 is a rear elevational view thereof.

Portions of the tether member have been omitted from

FIGS. 2 through 4 for ease of illustration.
